HEAT EXCHANGE AGITATOR

Fred M. Young, Racine, Wis., assignor to Young Radiator Company, Racine, Wis., a corporation of Wisconsin

Application January 9, 1956, Serial No. 558,052

4 Claims. (Cl. 138—38)

This invention relates to turbulence or agitator strips for the tubes of fluid heat exchangers, particularly those used for cooling the oil required in high-powered, high-heat producing engines.

It is well known that in tubular heat exchangers the tendency toward the equalization of temperature between the fluid flowing through the tubes and the fluid enveloping the tubes takes place through the tube wall. Where the fluid is flowing through the tube under pressure it is also well known that the column of fluid in effect comprises a concentric series of films or laminae, from the core to the circumference coincident with the inner face of the tube wall. Under pressure these concentric films or laminae tend to move successively slower from the core outwardly to the circumference where the film or lamina in frictional contact with the inner face of the tube wall moves the slowest; in fact, tends almost to immobility. Obviously, therefore, under such conditions the heat dissipation of the films or laminae of fluid is successively less from the circumference inwardly to the core, where the heat dissipation is at a very minimum. To overcome this decreasing heat dissipation, from the wall of the tube inwardly to the core of the fluid column, it has been a common practice to incorporate in the tubes some kind of fin, baffle, or turbulence strip. These are designed to slice or break-up and radially deflect these concentric fluid films or laminae so as to effect contact of all the fluid molecules with the heat-dissipating tube wall. The construction of such devices has followed a myriad of patterns in an attempt to get a reasonably high-temperature drop with a minimum pressure drop.

With the advent of increasingly high-powered, high-heat-creating engines, particularly for use in modern transport and military equipment, the heat exchange producers have been confronted with the demand for heat exchangers requiring less and less space yet capable of achieving an acceptable cooling of the coolant flowing through the tubes. This has forced the heat exchange manufacturers to reduce the size and increase the number of tubes they put into a heat exchanger. Such smaller units have necessitated the use of higher pressures in an attempt to attain the requisite temperature drop. On occasion, these tubes have been as small as $\frac{1}{16}$ " outside diameter. Clearly, any attempt to use internal agitators requires a very narrow and thin strip. This presents new problems in the design and form of effective agitator elements.

The main objects of this invention, therefore, are to provide an improved form of internal agitator especially for the smaller diameter tubes of heat exchangers; to provide an improved form of agitator of this kind capable of achieving a most practical high-temperature drop without too great a build-up in pressure; and to provide an agitator strip of this kind which is so simple to manufacture and insert into the tubes, as to make its production extremely economical.

In the accompanying drawings:

Fig. 1 is a perspective view of a strip of material which

2

has been cut to permit the formation of an agitator embodying this invention;

Fig. 2 is a perspective view of the agitator so formed; Fig. 3 is an enlarged, cross section of a tube with this improved agitator positioned therein;

Fig. 4 is an enlarged, fragmentary, longitudinal sectional view of the tube with this improved agitator in place therein; and

Fig. 5 is a perspective view of a fragment of a slight modification.

The distinctive concept of this invention involves a strip, usually very thin and narrow, with a staggered arrangement of arcuate-shaped lobes variously struck out from the opposite faces of the strip and on opposite sides of the longitudinal medial line.

The herein shown agitator, embodying this concept, comprises a metal strip 5 of thin, narrow width from which are struck out the lobes 6. For some types of heat exchangers, the strip may have to be as thin as 0.017 inch and narrow enough to be inserted into a tube of $\frac{3}{16}$ " outside diameter.

As so clearly shown in the drawings, the cuts which form the arcuate portions of the lobes 6 have radii the axes of which are located in the median line of the strip 5. Thus the arcs of these lobes 6 are in a circumference embracing the opposite edges of the strip 5. The diameter of such a circumference is just enough less than the inside diameter of the tube 10 to permit the agitator to slip into the tube with these arcuate peripheries of the lobes 6 practically in contact with the inside wall of the tube (see Fig. 3). Moreover, the arc of each lobe is materially greater than 90 degrees (see Fig. 3) so that the immediately successive lobes on opposite edges overlap the longitudinal median line of the strip 5. This overlap, at the peripheries of the lobes, is substantially one-quarter of the tube diameter. Such overlapping of the lobes insures a breakup of the laminar flow along the axis of the tube wherein these agitators are used.

The straight edges, which otherwise define the lobes 6, are here shown to be disposed at right angles to each other and are substantially parallel and normal respectively to the median line of the strip 5.

The cuts which form the lobes 6, may be variously arranged and the lobes variously struck out from the face of the strip 5. As shown in all of the figures except Fig. 5, the lobes 6 are arranged in pairs each successive pair along the strip being located on opposite sides of the median line. The lobes 6 of each pair are struck out from opposite faces of the strip, with the next adjacent lobes of successive pairs—on the opposite side of the median line—struck out from the opposite faces of the strip. As shown in Fig. 5, each successive lobe 6 is cut out on opposite sides of the median line. Moreover, such successive lobe is struck out from opposite faces of the strip.

Striking out of the lobes 6 forms an opening 9 adjacent each lobe. The strip 5 is inserted into the tube 10 so that the openings 9 are on the advancing side of the oil flow through the tubes. Thus, when such an agitator, as that herein shown, is in use, these lobes 6 and adjacent openings 9 are constantly breaking up the oil flow, causing the oil, in its traverse of the tube, to be deflected first from one side of the strip and then from the other as well as radially of the tube. This will materially reduce, if not entirely eliminate, the normal tendency toward laminar oil flow through the tubes not so equipped.

Variations and modifications in the details of structure and arrangement of the parts may be resorted to within the spirit and coverage of the appended claims.

I claim:

1. An agitator for tubular heat exchangers comprising a strip having arcuate-shaped lobes struck out transversely

from the opposite lateral edges thereof, the arc of each lobe being more than 90 degrees of a circle the periphery of which circle substantially embraces the opposite lateral edges of the strip, the axis of which circle is in the median line of the strip, the other edge of each lobe being straight and disposed transversely to the plane of the strip, the lobes struck out along opposite edges of the strip overlapping each other along their straight edges longitudinally of the strip, which overlap at the peripheries of the lobes is substantially equal to one quarter of the width of the strip.

2. An agitator for tubular heat exchangers comprising a strip having arcuate-shaped lobes struck out transversely from the opposite lateral edges thereof, the arc of each lobe being more than 90 degrees of a circle the periphery of which circle substantially embraces the opposite lateral edges of the strip, the axis of which circle is in the median line of the strip, the other edge of each lobe being straight and right-angularly disposed to the plane of the strip, the lobes struck out along one edge of the strip overlapping the lobes struck out along the other edge of the strip a distance substantially equal to one quarter of the width of the strip with the straight edges of the lobes parallel.

3. An agitator for tubular heat exchangers comprising a strip having successive pairs of arcuate-shaped lobes struck out alternately along opposite lateral edges of the strip, the arc of each lobe being more than 90 degrees of a circle the periphery of which circle substantially embraces the opposite lateral edges of the strip, the axis of which

circle is in the median line of the strip, the other edge of each lobe being straight and disposed transversely to the plane of the strip, the pairs of lobes struck out along the opposite edges of the strip overlapping each other along their straight edges longitudinally of the strip, which overlap at the peripheries of the lobes is substantially equal to one quarter of the width of the strip.

4. An agitator for tubular heat exchangers comprising a strip having successive pairs of arcuate-shaped lobes struck out alternately along opposite lateral edges of the strip, the arc of each lobe being more than 90 degrees of a circle the periphery of which circle substantially embraces the opposite lateral edges of the strip, the axis of which circle is in the median line of the strip, the other edge of each lobe being straight and right-angularly disposed to the plane of the strip, the pairs of lobes struck out along one edge of the strip overlapping the lobes struck out along the other edge of the strip a distance substantially equal to one quarter the width of the strip with the straight edge of the lobes parallel.
